INKWELL BASE

Loid Crandall, John W. Davis, and Lorentz J. Lindquist, Los Angeles, Calif., assignors to Harry A. Morgan, Los Angeles, Calif.

Application January 10, 1936, Serial No. 58,513

4 Claims. (Cl. 120—73)

This invention relates to a base for ink wells, lamps, telephones and the like and more particularly pertains to a cushion or pad bearing therefore.

It has heretofore been the practice in forming cushioned bearing faces for the bases of ink wells and other devices, such as lamps, telephones, and the like, to equip such base with a cushion the margin of which is exposed to view around the rim of the base, thus materially detracting from the appearance of the latter. The present invention contemplates the provision of a demountable resilient pad for the under side of a base or pedestal the margin of which will be concealed under a rim on the base in such fashion as to give the appearance of the base resting on such rim.

A particular object of the invention is to provide a base pad having the desirable feature of concealment as above pointed out which is so formed in conjunction with the base as to be readily assembled on the latter and whereby the pad may be easily removed and replaced.

Another object is to provide a base with a bottom facing of sheet resilient material, such as rubber or rubber composition, embodying a construction whereby the facing may be affixed to the base by frictional engagement therewith and the edge of the facing shielded.

With the foregoing objects in view together with such other objects and advantages as may subsequently appear the invention resides in the parts and in the combination, construction and arrangement of parts hereinafter described and claimed, and illustrated by way of example in the accompanying drawing in which:

Fig. 1 is a view of an ink well as seen in side elevation showing the invention as applied:

Fig. 2 is a detail in section taken on the line

40 2—2 of Fig. 1:

Fig. 3 is an inverted plan view of the base with portions broken away.

Referring to the drawing more specifically, A indicates generally a base which is here shown as comprising the base of an ink well, but which manifestly may constitute the base of a lamp, telephone, vase, tray or other object. The base is also shown as cylindrical but manifestly may be of any other contour.

In carrying out the invention the base is formed with a downwardly extending marginal flange 4 of rectangular cross section; the flange being here shown as protruding downwardly from a bottom wall 5 and projecting outwardly from an upstanding marginal wall 6 integral

with the bottom wall 5. Carried on the wall 6 and extending outwardly and downwardly therefrom is a rim 7 having an inturned marginal flange 8 on its lower edge which extends toward the outer margin of the flange 4 and terminates in spaced relation thereto on a plane slightly beneath the plane of the under side of the flange 4. As here shown the rim 7 is held in place on the wall 6 by a cap 9 having screw threads 10 screwed into engagement with the inner periphery of the wall 6; the cap 9 being formed with a flange 11 arranged to overlie a flange 12 on the upper edge of the rim 7 to clamp the flange 12 in relation to the upper margin of the wall 6.

A pad B formed of resilient sheet material such as rubber or rubber composition is formed to extend over the under side of the bottom wall 5 and is provided with a channel 14 of rectangular cross section adapted to receive the flange 4 in frictional engagement therewith. The pad B is formed of such thickness that when applied its underside will protrude slightly below the lower face of the flange 8 on the rim 7 and formed on the margin of the pad B is a lip 15 which is extended upwardly over the inner margin of the flange 8 to overlie the latter as particularly shown in Fig. 2, thus concealing the margin of the pad.

The under side of the pad is formed with ribs 16 for frictional engagement with the surface on which the base is supported.

The pad B being resilient and flexible is adapted to be readily applied to the base A which is effected by pressing the marginal portion of the pad through the space between the flanges 4 and 8 and forcing the flange 4 into engagement with the channel 14 which latter is formed of a cross section slightly less in width than that of the flange 4 so as to require slight expanding of the channel 14 to receive the flange 4 and whereby the side walls of the channel 14 will be placed under tension and will securely grip the side walls of the flange 4.

Manifestly the pad B may be readily removed and replaced and when mounted on the base will be practically concealed.

We claim:

1. In a base for ink wells and the like, a bottom wall formed with a downwardly extending marginal flange, a rim having an inturned marginal flange having its inner edge spaced from the outer margin of the flange on said bottom wall, and a resilient pad extending over the underside of said bottom wall provided with a

channel in which the flange on the bottom wall is engaged and having a marginal lip extending upwardly over the inner margin of the rim flange.

- 5 2. In a base for ink wells and the like, a bottom wall formed with a downwardly extending marginal flange, an upstanding marginal wall on said bottom wall, a rim carried by said marginal wall having an inturned flange spaced from the outer margin of the flange on said bottom wall, and a resilient pad extending over the underside of said bottom wall provided with a channel in which the flange on the bottom wall is engaged and having marginal lip extending over the inner margin of the rim flange.
- 10 3. In a base for ink wells and the like, a bottom wall formed with a downwardly extending marginal flange, an upstanding marginal wall on said bottom wall, a rim carried by said marginal wall having an inturned flange spaced from the outer margin of the flange on said bottom wall, and a resilient pad extending over the underside of said bottom wall provided with a channel in which the flange on the bottom wall is engaged and having marginal lip extending over the inner margin of the rim flange.
- 15 4. In a base for ink wells and the like, a bottom wall formed with a downwardly extending marginal flange, an upstanding marginal wall on said bottom wall, a rim carried by said marginal wall having an inturned flange spaced from the outer margin of the flange on said bottom wall, and a resilient pad extending over the underside of said bottom wall provided with a channel in which the flange on the bottom wall is engaged and having marginal lip extending over the inner margin of the rim flange.
- 20 5. In a base for ink wells and the like, a bottom wall formed with a downwardly extending marginal flange, an upstanding marginal wall on said bottom wall, a rim carried by said marginal wall having an inturned flange spaced from the outer margin of the flange on said bottom wall, and a resilient pad extending over the underside of said bottom wall provided with a channel in which the flange on the bottom wall is engaged and having marginal lip extending over the inner margin of the rim flange.

the outer margin of the flange on said bottom wall, a resilient pad extending over the underside of said bottom wall provided with a channel in which the flange on the bottom wall is engaged and having a marginal lip extending over the inner margin of the rim flange, and a cap affixed to said marginal wall having a flange over-lying the upper margin of said rim and clamping the latter on said wall.

4. In a base for ink wells and the like, a resilient pad formed with a marginal lip and having a continuous channel on its upper face extending contiguous said lip, means engaging said channel to hold said pad, and means engaging said lip extending over and under the margin thereof to conceal the edge of said pad.

LOID CRANDALL.

JOHN W. DAVIS.
